DELIVERY MECHANISM FOR PRINTING PRESSES

Filed Aug. 20, 1930

Inventor,
Nils C. Andersen,
By Fricke & DeBuse,
Attorneys.

UNITED STATES PATENT OFFICE

1,928,923

DELIVERY MECHANISM FOR PRINTING PRESSES

Niels C. Andersen, Chicago, Ill., assignor to The Goss Printing Press Co., Chicago, Ill., a corporation of Illinois

Application August 20, 1930. Serial No. 476,524

6 Claims. (Cl. 271—88)

My invention relates to delivery mechanism for printing presses, and has for its object the provision of a new and improved form and arrangement of parts by which the folded products in the form of complete papers or pamphlets or in the form of signatures or other parts of a magazine or book may be stacked evenly in a pile for convenient handling. It is another object of my invention to provide an improved arrangement by reason of which the pile of folded products may be withdrawn readily and quickly from position so as to permit a new pile to be stacked.

It is another object of my invention to improve devices of this type in sundry details hereinafter pointed out. The preferred means by which I have accomplished my several objects are illustrated in the drawing and are hereinafter specifically described. That which I believe to be new and desire to cover by Letters Patent is set forth in the claims.

In the drawing,—

Fig. 1 is a top plan view of the preferred form of my improved apparatus; and

Fig. 2 is a side view of the structure as shown in Fig. 1, with certain of the parts broken away for clearness of illustration, and showing in dotted lines a changed position of certain of the parts.

Referring now to the two figures of the drawing, in which corresponding parts are indicated by the same reference characters, 10 indicates a base from which rises a frame-work 11. Upon the frame-work 11 is mounted an endless belt 12 comprising conveyer means by which a series of papers are delivered toward the left in Fig. 1 from a printing press. In the construction shown the belt 12 is supported by a roller 13 which is driven by a sprocket chain 14 operating upon a sprocket gear 15 carried by said roller. Inasmuch as the operation of the delivery belt of the printing press is fully understood, it is believed to be unnecessary to illustrate any part of the press other than the delivery belt 12 thereof as above described.

In the base 10 opposite the end of the frame-work 11 and the conveyer belt 12, I have provided a series of standards 16 in the form of rods upon which a platform 17 is slidably mounted, such platform being supported by means of coiled springs 18 mounted on the rods 16 underneath the platform. Collars 19 are provided on the upper ends of the rods 16 serving to limit the upward movement of the platform. The arrangement is such that when the platform 17 is not provided with a load the top face of the

platform stands substantially at the level of the top face of the conveyer belt 12. The arrangement further is such that, upon delivery of a signature or other folded product into position upon the platform, the platform is adapted to descend slightly against the action of the springs so as to bring the top face of such folded product substantially to the level of the top face of the delivery belt. As a result of this arrangement, in which the platform descends slightly upon the delivery of each additional paper into position thereon for keeping the upper surface of the pile of papers at all times in substantial alignment with the face of the delivery belt, but at a slightly lower level than that of the top face of the belt, successive papers are delivered smoothly and evenly to the pile. In the arrangement shown in Fig. 2, a signature 20 is shown in position upon the platform 17, with a plurality of additional signatures 21 partially supported by the platform 75 as they are delivered in overlapping arrangement by the conveyer belt.

For holding the signatures from slipping sideways off the delivery belt 12, I have provided shields 22 of any approved type mounted in position by means of brackets 23. Upright guide plates 24 and 25 of any approved type are mounted upon the base 10 by means of supporting bars 26 so as to have their inner faces in alignment with the inner faces of the shields 22. For holding the signatures down into operative engagement with the delivery belt 12, I have provided a heavy roller 27 revolvably mounted by means of a bracket 28 above the roller 13 upon which the belt 12 is mounted. The bracket 28 in turn is carried by a rock shaft 29 journaled between the shields 22. This roller 27 is light enough to permit successive papers to pass readily under it and is heavy enough for keeping the successive signatures under the influence of the delivery belt sufficiently for effecting a delivery of such signatures toward the left into position to be supported fully by the platform 17.

At the outer end of the plate from 17, I have provided stop means in the form of an arm 30 pivotally mounted upon a horizontal bar 31. At its lower end the arm 30 is provided with a short arm 32 in angular position, to the lower end of which arm 32 is connected a link 33. Upon the link 33 I have mounted a coil spring 34, one end of which bears against a collar 35 carried by the link 33 and the other end of which bears against a bracket 36 rising from the base 10. The arrangement is such that the

spring 34 normally holds the arm 30 in the position as shown in solid lines in Fig. 2, in which position the arm serves to stop the outward movement of successively delivered signatures. 5 When upon the continued operation of the press and the delivery belt 12 a pile of signatures or other folded products have accumulated upon the platform 17 in neatly piled superposed position thereon, an operator is able to grasp such 10 pile by the outer corners thereof and withdraw the same very readily and quickly toward the left in said Figs. 1 and 2, the arm 30 being adapted to yield readily against the action of the spring 34 into the position as shown in dotted lines in Fig. 2 for permitting such removal of the papers. The springs 18 thereupon bring the platform 17 again to its elevated position ready to receive the next successive signature from the delivery belt. At the same time the 15 spring 34 serves to bring the arm 30 again to normal position as shown in solid lines.

For providing additional assurance that the papers will be kept in evenly piled arrangement on the platform, I have provided means for 20 jostling the papers slightly as they are delivered. In the construction illustrated, this jostling effect is brought about through the medium of the arm 30 which is given a limited swinging movement toward and from the platform. The 25 spring 34 serves to provide the movement toward the platform 17 when it is released after a movement away from the platform. The means for effecting movement of the arm away from the platform against the action of the spring 30 34 comprises a yoke lever 37 mounted upon a rock shaft 38. The shaft 38 is actuated by means of a lever 39 mounted on said shaft, with its 35 free end connected to an upwardly extending link 40. The upper end of the link 40 is engaged during a portion of the rotation of the sprocket gear 15 by a pin 41 extending outwardly from said gear, such pin 41 serving to force the link 40 downwardly. This movement of the 40 link serves to rock the shaft 38, causing the lever 37 to swing toward the right in Fig. 2, serving by engagement with a pin 42 carried by the link 33 to move the link 33 toward the right in said figure so as to swing the arm 30 toward the left. When the pin 41 in the 45 rotation of the gear 15 reaches the lower part of its movement it passes out of engagement with the upper end of the link 40, whereupon the spring 34 is free to move the arm 30 again toward the right into engagement with the face of the pile 50 of signatures upon the platform 17 so as to deliver a light blow upon any paper extending slightly beyond the face of the pile. This intermittent jostling movement of the arm 30 serves to keep the edges of the signatures in evened 55 position with respect to each other.

While I prefer to employ the construction substantially as shown in the drawing and as above described, it is to be understood that my invention is not limited thereto except so far as the 60 claims may be so limited by the prior art, it being understood that changes may well be made in the construction without departing from my invention.

I claim:

1. In a mechanism of the type described, the combination of a base, a plurality of standards rising from said base in spaced position thereon, a platform slidably mounted on said standards, springs on said standards for supporting said 65 platform yieldingly in position and for keeping

the platform in normal horizontal position as it descends under pressure, means at one end of the platform for delivering folded products successively to the platform, a stop arm at the opposite end of the platform extending upwardly beyond the normal uppermost position of said platform and pivotally mounted on a horizontal axis located a short distance above the lower ends of said standards, and yielding means for holding said arm normally in upright position closely adjacent to the end of the platform, the arrangement being such that said arm is readily movable against the action of said yielding means in the direction away from the platform so as normally to permit removal of the accumulated pile of folded products from the platform by a direct horizontal movement of said folded products. 80

2. In a mechanism of the type described, the combination of a base, a plurality of standards rising from said base in spaced position thereon, a platform slidably mounted on said standards, springs on said standards for supporting said platform yieldingly in position and for keeping the platform in normal horizontal position as it descends under pressure, means at one end of the platform for delivering folded products successively to the platform, a stop arm at the opposite end of the platform extending upwardly beyond the normal uppermost position of said platform and pivotally mounted on a horizontal axis located a short distance above the lower ends of said standards, and yielding means for holding said arm normally in upright position closely adjacent to the end of the platform, the arrangement being such that said arm is readily movable against the action of said yielding means in the direction away from the platform so as normally to permit removal of the accumulated pile of folded products from the platform by a direct horizontal movement of said folded products. 85

90

3. In a mechanism of the type described, the combination of a base, a plurality of standards rising from said base in spaced position thereon, a platform slidably mounted on said standards, springs on said standards for supporting said platform yieldingly in position and for keeping the platform in normal horizontal position as it descends under pressure, means at one end of the platform for delivering folded products successively to the platform, a stop arm at the opposite end of the platform extending upwardly beyond the normal uppermost position of said platform and pivotally mounted on a horizontal axis located a short distance above the lower ends of said standards, and yielding means for holding said arm normally in upright position closely adjacent to the end of the platform, the arrangement being such that said arm is readily movable against the action of said yielding means in the direction away from the platform so as normally to permit removal of the accumulated pile of folded products from the platform by a direct horizontal movement of said folded products. 95

4. In a mechanism of the type described, the combination of a base, a plurality of standards rising from said base in spaced position thereon, a platform slidably mounted on said standards, springs on said standards for supporting said platform yieldingly in position and for keeping the platform in normal horizontal position as it descends under pressure, means at one end of the platform for delivering folded products successively to the platform, a stop arm at the opposite end of the platform extending upwardly beyond the normal uppermost position of said platform and pivotally mounted on a horizontal axis located a short distance above the lower ends of said standards, a short arm at an angle to said stop arm below its pivotal axis and adapted to swing with the stop arm about said axis, a link pivotally connected with said short arm and extending backwardly between said standards, means comprising a coiled spring on said link adapted yieldingly to resist swinging movement of said stop arm from its upright position but adapted to permit movement of the stop arm away from the platform for removal of the accumulated folded products from the platform by a direct horizontal movement of said folded products, and means actuated by said product delivering means for giving said link a backward movement at intervals for swinging the arm away from the platform and adapted to release the link for a quick return of the arm by said spring. 80
5. In a mechanism of the type described, the combination of a base, a plurality of standards rising from said base in spaced position thereon, a platform slidably mounted on said standards, springs on said standards for supporting said platform yieldingly in position and for keeping the platform in normal horizontal position as it descends under pressure, means at one end of the platform for delivering folded products successively to the platform, a stop arm at the opposite end of the platform extending upwardly beyond the normal uppermost position of said platform and pivotally mounted on a horizontal axis located a short distance above the lower ends of said standards, a short arm at an angle to said stop arm below its pivotal axis and adapted to swing with the stop arm about said axis, a link pivotally connected with said short arm and extending backwardly between said standards, means comprising a coiled spring on said link adapted yieldingly to resist swinging movement of said stop arm from its upright position but adapted to permit movement of the stop arm away from the platform for removal of the accumulated folded products from the platform by a direct horizontal movement of said folded products, a rotary driven member, a pin eccentrically mounted on said rotary member, a second link slidably mounted in position with its upper end in position to be engaged by said pin for giving the link a downward movement, and means actuated by said downward movement of said second link for moving said first named link backwardly against the action of said pin for swinging said arm, said pin being adapted in its rotation to move out of engagement with said second link for permitting the spring to return said arm quickly to its normal upright position. 85
6. In a mechanism of the type described, the combination of a base, a plurality of standards rising from said base in spaced position thereon, a platform slidably mounted on said standards, springs on said standards for supporting said platform yieldingly in position and for keeping the platform in normal horizontal position as it descends under pressure, means at one end of the platform for delivering folded products successively to the platform, a stop arm at the opposite end of the platform extending upwardly beyond the normal uppermost position of said platform and pivotally mounted on a horizontal axis located a short distance above the lower ends of said standards, a short arm at an angle to said stop arm below its pivotal axis and adapted to swing with the stop arm about said axis, a link pivotally connected with said short arm and extending backwardly between said standards, means comprising a coiled spring on said link adapted yieldingly to resist swinging movement of said stop arm from its upright position but adapted to permit movement of the stop arm away from the platform for removal of the accumulated folded products from the platform by a direct horizontal movement of said folded products, a rotary driven member, a pin eccentrically mounted on said rotary member, a second link slidably mounted in position with its upper end in position to be engaged by said pin for giving the link a downward movement, and means actuated by said downward movement of said second link for moving said first named link backwardly against the action of said pin for swinging said arm and arranged for permitting backward movement of said first named link independently of movement of second link, said pin being adapted in its rotation to move out of engagement with said second link for permitting the spring to return said arm quickly to its upright position. 90
